UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING APPARATUS.

Application filed January 14, 1916, Serial No. 72,044. Renewed October 7, 1920. Serial No. 415,276.

To all whom it may concern:

Be it known that I, EDMUND C. MORGAN, a citizen of the United States, residing at New York, in the county of New York and State of New York, have invented certain new and useful Improvements in Mining Apparatus, of which the following is a specification.

This invention relates to improvements in mining machines and accessory apparatus, and has for its object, the provision of apparatus of this character, which shall be of novel and improved construction and which shall facilitate mining operations.

The invention is exemplified in the combination and arrangement of parts illustrated in the accompanying drawings, and described in the following specification, and is more particularly pointed out in the appended claims. In the drawings,

Fig. 1, is a section through the face or wall of a vein of coal showing one form of mining machine constituting a part of the present invention in operative position.

Fig. 2, is a side elevation of the machine shown in Fig. 1.

Fig. 3, is a section on line 3—3 of Fig. 2.

Fig. 4, is a top plan view of the machine shown in the various figures, but, with the cutter head removed.

Fig. 5, is a fragmentary view substantially on line 5—5 of Fig. 4.

Fig. 6, is a rear elevational view of the rotary cutter head forming a part of the present invention with the cutter frame in horizontal position.

Fig. 7, is a transversed sectional view on line 7—7 of Fig. 6.

Fig. 8, is a transversed sectional view on line 8—8 of Fig. 6.

Fig. 9, is a transversed sectional view on line 9—9 of Fig. 6.

Fig. 10, is a longitudinal sectional view of the cutter head taken on the plane of division of the casing.

Fig. 11, is a sectional view of a mine chamber showing the mining machine forming a part of this invention in its relation to the accessory apparatus.

Fig. 12, is a view similar to Fig. 11, but showing a slightly modified form of mining machine and accessory apparatus.

Fig. 13, is a diagrammatic plan view of a portion of a coal mine showing the conveyor system used in connection with the present invention.

Fig. 14, is a diagrammatic vertical sectional view of a portion of a mine showing the relation of the various parts of the apparatus comprised in the present invention.

Fig. 15, is a diagrammatic plan view of the layout of a mine in which the apparatus embodying the present invention is used.

The construction of the machine comprised in the present invention, will best be understood by reference to Figs. 1 to 10 inclusive of the drawings. As best shown in Figs. 1, 2 and 3, the main frame of the machine, is of general rectangular form and in operating position, is placed with one lateral

surface toward the face of the material to be operated upon. The frame is provided with uprights 1 and 2 at opposite ends thereof, the uprights being connected at the bottom and top by members 3 and 4 respectively, extending longitudinally of the

frame. Extending to the front and rear of the members 3 and 4, are supporting brackets 5, there being two brackets at each end of the machine. Each pair of brackets 5, is provided with a roller 6, which form

the main support for the machine. The rollers 6, are provided with axels 7, journaled in the brackets 5. Extending laterally from the inner faces of the uprights 1 and 2, on the side of the frame toward the wall from

which the coal is being severed, are two guard plates 8 and 9, there being one plate at each end of the machine. These plates, as shown in Figs. 1 and 3, are shaped at their lower edges to conform to the shape

of the wall from which the material is being removed and are integral at their lower edges with the longitudinal extending member 3. The upper longitudinal extending member 4, is secured to the uprights 1 and 2, by lag screws 10, and is provided with a horizontal platform or shelf 11, on which a motor 12, for operating the mining machine is mounted. Extending outwardly

from each of the uprights 1 and 2, are bracket members 13, which carry internally threaded sleeves 14, shown best in Figs. 1, 2 and 4. The sleeves 14, are provided with screws 15, and pointed extensions 16 at the upper ends. Hand wheels 17, are rigidly secured to the extensions 16 for operating the

screws 15 in the sleeves 14, to force the extensions upwardly into contact with the roof of a mine for holding the machine frame rigidly in an upright position.

The uprights 1 and 2, as shown best in Figs. 1, 4 and 5, are each provided with vertical slideways 18. A bar 19, extending longitudinally of the machine frame, is provided at each end with a slide 20, which fits over the slideways 18 and is guided for vertical movement thereon. The bar 19, is provided at the central portion thereof, with a lug 21, which extends laterally relative to the main frame of the machine into a position directly below a corresponding lug 22, secured to the upper edge of the plate 4, Figs. 3 and 5. The lug 21, is threaded to receive a screw 23, which passes freely through an opening in the lug 22, and which is provided at its upper end with a head 24 and a hand wheel 25, for rotating the screw to adjust the bar 19 vertically on the uprights 1 and 2. The slides 20, have rigidly secured thereto, a pair of brackets 26 and 27 respectively. These brackets extend from the side of the machine toward the wall of material to be mined, and are provided at their outer extremities with bearing rings 28. These rings form vertically adjustable journal supports for a cutter head 30 to be described, and are movable up and down, by the rotation of the hand wheel 25.

The construction of the cutter head 30 itself, will best be understood, by reference to Figs. 6 to 10 inclusive. The main body of the cutter head consists of upper and lower casing sections 31 and 32 respectively, which are secured together by bolts 33, to form a hollow cylindrical casing or axel, which is supported for rotation in the bearing rings 28 and which encloses the operating mechanism for a chain cutter 34. The hollow axel made up of the sections 31 and 32, is not mounted directly in the bearing rings 28, but, is slidably secured at its opposite ends to bearing members 35 and 36 respectively. These members 35 and 36, are provided with bearing surfaces 37 and 38 respectively, which are mounted for rotation in the bearing rings 28. On the sides of the bearing members 35 and 36 and opposite the bearing surfaces 37 and 38, are secured supporting members 40, having grooves 41, on which the hollow axel is supported for sliding movement to adjust its central axis relative to the axis of rotation of the bearing members 35 and 36 in the rings 28. The supporting members 40, as shown in Figs. 9 and 10, extend some distance on each side of the hollow axel to permit considerable lateral adjustment of the axel relative to the center line of the journals 28. The hollow axel is slidably secured to the supporting members 40 by plates 42, there being one plate secured to each end of the members 31 and 32. Each of the plates 42, is provided with a flange or guideway 45, which flanges fit in the grooves 41 of the supporting members 40. The plates 42, are secured to the

ends of the members 31 and 32, by lag screws 46, as shown in Figs. 6 and 9. By this construction, bearing discs having a common fixed axis of rotation, are journaled in the bearing rings 28, and the main portion of the cutter head is slidably supported by the inner faces of these discs in a manner to permit lateral movement of the central axis of the head relative to the axis of rotation of the discs.

The shifting of the cutter head casing relative to the supporting discs, is accomplished by means of a rack and pinion construction, best shown in Figs. 9 and 10. The inner portion of the supports 40, are provided with rack teeth 48, which mesh with pinions 49, one of which is carried on each end of the shaft 50, which extends longitudinally of the cutter head frame, and which is journaled in bearings 51 carried in the frame. Secured to the shaft 51, intermediate the ends thereof and within the opening in the interior of the cutter head casing, is a worm wheel 52, which meshes with a worm 53, journaled in bearing lugs 54, secured to the interior of the cutter head casing, as best shown in Fig. 3. As shown in this figure, the wall of the cutter head casing, is provided with a recess 55, into which a square head 56 of the worm shaft 57 extends. To adjust the cutter head casing relative to the axis of rotation, a detachable hand crank is fitted to the square head 56 of the shaft 57, and the worm 53 is rotated to drive the worm wheel 52 and the shaft 50. This rotates the pinions 49, in mesh with the racks 48, and causes the cutter head casing to be shifted relative to the axis of rotation of the bearing members 35 and 36. This shifting of the cutter head casing moves the cutter chain 34 and its supporting frame 60 relative to the axis of rotation of the cutter head, and thus changes the effective radial length of the cutter frame, to adjust the size of the cut made by the chain. In working in a comparatively low vein where the cuts like those designated by the broken lines *a*, in Fig. 1, have a comparatively short radius, the cutter head 30 and the cutter frame 60 attached thereto, are moved backwardly relative to the axis of rotation of the cutter head, so that the effective radius arm of the cutter frame is comparatively short. At the same time, the supporting brackets 26 for the cutter head, are moved downwardly by rotation of the hand wheel 25 and screw 23, to bring the extremity of the cutter frame when swung to its lowermost position on a level with the lower portion of the supporting rollers 6. In this way, the extreme upper reach of the cutter bar is moved downwardly a distance equal to the combined movement of the supports 26 on the main frame and of the cutter bar 60 relative to the axis of rotation of the

cutter head. If the machine is working in a comparatively thick vein, the cutter bar 60 is moved outwardly relative to the axis of rotation of the cutter head, and at the same time the supports 26 are moved upwardly on the main frame, so that in operation, the extremity of the cutter bar will move through arcs, indicated by the broken lines *b*, in Fig. 1. An intermediate position is indicated by the full lines in this figure. The inner ends of the cutter bar 60, are held in place relative to the upper section 31 of the hollow cylindrical axel by the plates 42, which clamp the bar rigidly against the ends of the section 31, as shown in Figs. 6 and 8. The cutter head 30, is rotated in its bearings 28, by means of a grooved pulley 61, secured to the bearing disc 38 outside of the bearing ring 28, as shown in Fig. 10, by lag screws 62 passing through the pulley into the bearing disc. The pulley 61 is thus rigidly secured to the bearing disc, and at the same time forms a stop for enclosing the bearing ring 28 and holding the cutter head from longitudinal movement relative to the ring. The pulley 61, is provided with a peripheral groove 63 to accommodate a cable 64, Figs. 1 and 2, which is carried to a drum 65, on which it is wound. The cable 64, has one end secured to the pulley 61 in such a position that the cable is wound once substantially entirely around the pulley, when the cutter frame 60, is in its lowermost position. It will be apparent that tension upon the cable due to rotation of the drum 65, will cause the pulley 61 to rotate in a counter-clockwise direction, as viewed in Fig. 1, moving with it the cutter frame 60 for making a cut in the face of the vein of material to be mined.

The drum 65, is driven from the motor 12, through a system of reduction gearing enclosed in the casing 66 which gearing drives the shaft 67 at a reduced speed. The shaft 67, is geared to the shaft which carries the drum 65, by spur gearing enclosed in the casing 68. The connection between the shaft 67 and the drum 65, is controlled by a clutch 69, operated by a handle 70, carried on the face of the gear casing 68, as shown in Figs. 1 and 2. The motor 75, for driving the cutter chain 34, as shown in Fig. 10, is journaled in transversely extending walls 76 and 77, which form a central enclosed chamber in a hollow axel for the cutter head, in which chamber the motor operates. The shaft 50, which passes through the motor chamber, is preferably made of a non-magnetic metal, such as phosphor bronze, so that it will not interfere with the magnetic field of the motor. The motor shaft 78, extends through the wall 77, and is provided with a pinion 79, which meshes with a gear 80, secured to a stub shaft mounted for rotation in the wall 82 of the cutter head casing, and which drives a bevel pinion 83, which drives a sprocket wheel 84, carried on a transversely extending shaft 85. A chain 34, passes over the sprocket wheel 84, and is thus driven through the connecting gearing by the motor 75, to form the kerf in the material as the cutter frame 60 is fed forwardly therein. The inner run of the chain 34, is guided along the slideway 86, extending longitudinally of the cutter head casing, and at the end of the cutter head opposite the sprocket wheel 84, is an arcuate curved guideway 87, which guides the chain around the angular turn at that end of the cutter head. A similar guide 88, is provided at the end of the cutter head adjacent the sprocket wheel 84, to guide the chain onto the wheel. The movement of the chain 34, is controlled by the motor controller, which may be located in any suitable position on the frame of the mining machine.

As shown in Figs. 1 and 3, the cutter chain 34, severs a crescent-shaped section of material from the face of the vein as the frame 60 is swung upwardly about its axis of rotation. In order to remove the severed material to a position from which it may be transported from the mine, a series of cables 90, have their ends secured to the rear edge of the outer bar of the cutter frame 60, and are drawn into the kerf formed by the chain 34, as the cutter frame is swung upwardly about its axis. The opposite ends of the cables 90, are secured to an elongated drum 91, which is mounted on a shaft 92, extending longitudinally of the main frame near the lower portion thereof, and journaled for rotation in bearings 93 and 94. The shaft 92, is free to slide longitudinally in the bearing 93, but, is provided with threads 95, which mesh with corresponding threads in the bearing 94. As the shaft 92 is rotated, it will be seen that it will also be fed longitudinally in its bearings by the threads 95. The pitch of these threads, is made to correspond with the diameter of the cables 90, so that as the cables 90 are wound upon the drum 91, the drum will be moved longitudinally a proper amount to maintain the portion of the cable being paid onto or off the drum in a constant fixed position relative to the machine frame and to the cutter frame. The shaft 92, is driven by a sprocket chain 86, which drives a sprocket wheel splined to the shaft 92, and which is driven by a sprocket wheel on the shaft 67, arranged to be clutched thereto by a clutch 98, operated by a lever 99, as shown in Figs. 2 and 4. As the cutter frame 60, is fed upwardly, the shaft 92, is permitted to rotate freely in its bearings 93 and 94, to pay out the cables 90, as they are drawn onto the kerf formed by the cutter. When the cutter frame has completely severed a section of material from the mine wall, the severed material will

be received by the cables 90, which together form in effect a sling for receiving the material. The material will usually break up and fall downwardly somewhat by its own weight, as indicated in Fig. 3. From this position, it is drawn backwardly over the plate 3 and drum 91, by rotating the drum to wind the cables 90 thereon by the mechanism described to insure the movement of the severed material with the cables. A plate 100, Fig. 3, is pivoted to the rear portion of the outer bar of the cutter frame 60, and has a limited movement in a clockwise direction about its pivot, as shown in that figure. As the cables are wound upon the drum, this plate 100, will be drawn into contact with the severed material and will move the material with it and discharge it over the top of the drum 91 onto transporting mechanism to be described. The plate 100, is slightly curved and is free to swing into a position to be drawn into the kerf by the cutter frame during the cutting operation, as indicated in Fig. 1. During the return movement, the cable 64, is permitted to unwind from the drum 65, to permit the cutter frame 60, to be returned to its original position.

In the operation of the machine, cuts are made in succession along the face of the vein one after another, the machine being adjusted along the face a distance equal to the width of a cut after each operation. Because of this mode of working, one edge of each section of severed material is always left exposed, and it is necessary to provide means for preventing the material from falling off the rope sling at this edge. To accomplish this purpose, sheet metal shields 101 and 102, are provided, one at each end of the machine frame. These shields, at their edges are curved to conform to the curvature of the cut made by the loop cutter and are journaled at one of their ends on pivot pins 103 and 104 respectively, extending outwardly from the plates 8 and 9. Each of the guard plates, are provided with openings 105 and 106. The plates 8 and 9, are also provided with openings at their outer ends arranged to register with the openings in the pivoted guard plates, and bolts 107, are provided to pass through the registering openings and hold the guard plates in either of two positions, as indicated in Fig. 1. The guard plate on the end of the machine toward which the machine is moved after each cut, is secured in its upper position by passing the bolt 107 through the lower hole 105, while the plate on the opposite end of the machine is secured in its lower position so that its curved edge will substantially conform to the curvature of the cut being made, and so that the plate will enclose the exposed surface of the cut and prevent the material from

escaping from the rope sling. To change the guard plates from one position to the other, it will be necessary to remove the bolt 107, and slide the pivoted plate along the pin 103, so that in its upper position it will free the end of the cutter head 30, while in its lower position it will be held firmly against the edge of the fixed guard plate and in line with an arm of the cutter frame 60. The pivot pins 103 and 104, are made of sufficient length to permit this movement of the pivoted guard plates longitudinally thereof. Each of the pivoted guard plates, is provided with a shoe 110, which is fastened to the periphery thereof in position to bear upon the mine floor when the plate is secured in its lowermost position. This gives an added point of support to the machine and assists in counteracting the pressure produced by the feeding movement of the cutter frame.

For the purpose of moving the machine along the face of the vein after each cut has been made, a motor 112 is mounted on one end of the machine frame, as shown best in Figs. 2 and 4. This motor is geared to a drum 113, which carries a cable 114, arranged to be wound thereon. The cable 114, may be carried in either direction from the winding drum and may be secured at its end to any fixed object. By winding the cable on the drum 113, the machine may be moved in either direction along the face of the wall, depending of course, on the direction in which the cable 114 extends from the drum.

It should be noted that the rollers 6 are in alinement with each other, as shown in Fig. 2, in an upright plane which extends along the mine wall and through the supporting frame and the roof jacks. The movement of the supporting frame along the mine wall is therefore along a mono-path as illustrated in Fig. 11 or along a mono-rail *g* as illustrated in Fig. 12, in that one of the rails of the usual track is dispensed with. As shown in Figs. 11 and 12, the core cutting mechanism is fed in planes which are substantially perpendicular to the upright plane which extends through the rollers, the supporting frame, and the roof jack. Such feeding movement of the core cutting mechanism transversely of the narrow frame, enables the core to be dislodged, as shown in Fig. 3, for movement through the rectangular opening in the supporting frame shown in Fig. 2, directly onto the endless travelling conveyer *k*. By providing a supporting frame comparatively narrow in a direction extending transversely back from the mine wall, I am enabled to place the endless conveyer *k* closer to the wall being operated on and consequently the roof props may be made less in strength and less in number because of the decreased tendency

for the roof to fall as the solid pillars are approached from the space which has been mined, as illustrated in Fig. 15.

Attention is also called to the fact that in Fig. 12, the roof props carry sections of the mono-rail *q* which sections can be moved forwardly to new locations, as illustrated in Fig. 15 whenever the core cutting mechanism has cut a core and the frame carrying such cutting mechanism is moved along the mine wall to a new location. When the last core has been cut across the rear end of the coal pillar, as illustrated in Fig. 15, the section *q* of the mono-rail may be moved forward together with the mining machine when all of the sections of the mono-rail will be in lateral alinement for movement of the mining machine step by step along the mine wall in the opposite direction. The lower plates *p* of the roof props, in addition to carrying the mono-rail sections *q*, also carry the endless conveyor *k* which, when the last mono-rail section is moved forward for starting the cutting of a section across the mine pillar in the opposite direction, may be shifted along the supporting plate *p* to a position adjacent the mono-path of travel of the frame. In the same manner that the rail sections are placed in alinement with each other, the grooves at the under side of the forward end of the roof prop plate *n* are moved forward to occupy positions in alinement with each other to receive the upper ends *n'* of the roof jacks mounted in spaced apart positions on the frame, as shown in Figs. 2 and 12.

To prevent portions of the material which may be severed from the upper extremity of the cut from falling onto parts of the machine which are liable to breakage, a shield 115, Figs. 1 and 4, is carried by braces 116 and 117, extending upwardly from the vertically adjustable support for the cutter head. This shield is so positioned, that it will intercept portions of material that may fall from the upper extremity of the cut and direct them onto the hollow axel of the cutter head and thence into the rope sling 116 for receiving the severed material.

While the machine described may be used in connection with any of the well known devices for transporting coal from a mine, in order to secure the greatest advantages of the machine, the invention contemplates its use in combination with a system of conveyors, shown in Figs. 11 to 15 inclusive. As shown in Fig. 15, the mine is laid off in sections by entries *e*, and cross entries *d*, leaving intermediate pillars of coal *e*. It is desirable to remove the coal from two pillars *e* simultaneously by a pair of machines working in conjunction with one another, as indicated at *f*, in Fig. 15. A track *g*,

may be laid in the entry *d*, between the two pillars being worked, and at the end of the track a conveyor *h* is placed which forms an extension feeder to the track proper. This conveyor *h*, is given a slight inclination, as shown in Fig. 14, so that it may discharge material from one end into a car *i*, running on the track *g*. The end of the conveyor *h*, opposite the discharge end, rests upon the surface of the mine chamber in position to receive material from two laterally extending conveyors *k* and *l*, which extend the full length of the end face of the pillars *e*, as indicated in Fig. 13. These conveyors may be driven by any suitable and well known power device, not shown in the drawing, and it is desirable to arrange the driving mechanism for the conveyors *k* and *l*, so that they may be driven in either direction. The roof of the mine adjacent the surface of the vein being worked, is supported by a series of props *m*, as shown in Figs. 11, 12 and 13. These props, are provided at their upper extremity with laterally extending arms *n*, and at their lower extremity with similar arms *p*. The lower arms *p*, extend toward the face of the vein being worked into a position adjacent that occupied by the mining machine and the conveyors *k* and *l*, are made to rest upon these arms. After the machine progresses along the face of the vein apart a given prop *m*, that prop is moved toward the face of the vein, as indicated at *m'*, in Figs. 11, 12 and 15. The arms *p*, are of sufficient length to support the conveyor, whether the props *m* are in the position shown in full lines, or in the advanced position shown in broken lines, in Fig. 11. As the props are moved forward, the roof of the mine from which they are moved, is left unsupported to fall from the weight of the superimposed material. Fig. 12, shows a slightly modified form of construction, in which the arms *p*, are provided with ribs *q*, which when a series of props are placed side by side, form a track on which the mining machine is supported. Where this form of prop is used, the roller 6 of the mining machine, will be modified to correspond with the track on which it runs. The upper arms *p*, may also be provided with grooves *n'* to receive the upper end of the extension bar 16 for holding the machine in upright position.

In operation, the machines are preferably worked in pairs, as indicated in Fig. 15, each machine severing material from the face of the vein at corresponding positions in adjacent pillars *e*. After each cut made by one of the machines, it is moved along the face of the vein into position to make the next cut. In this way for each passage of the machine across the face of the vein,

it severs a section of material crescent-shaped in cross section from the entire length of the face being worked. As the material is severed from the face of the vein,

5 it is discharged from the machine onto the conveyor which is properly positioned to receive and transport the severed material. The two conveyors which receive the material from the two machines working in

10 conjunction with one another, carry this material to the main conveyor positioned in the entry between the two sections of the mine being worked, where it is received from the contributory conveyor onto the

15 main conveyor and carried upwardly and discharged onto a car, by means of which it is transported from the mine. The machines are operated to sever material as they are moved in either direction, the only

20 changes necessary for reversing the operation being the adjustment of guard plates 101 and 102, and the change of the direction of the cable 114 for moving the machine. As the machines progress along the

25 face of the vein, the props are moved forwardly in succession, and after the machines have moved completely across the face, the conveyors are all shifting forwardly into position for the next series of

30 cuts. It is clear, of course, that any number of machines desired, may be used in conjunction with one another.

If a vein of coal is encountered which has a stratum of undesirable material, it may

35 be found advantageous to operate one of the mining machines constituting a part of the present invention in conjunction with any machine of well known construction for making a horizontal kerf in the mine wall. One of the machines, shown in Fig. 15, will

40 be replaced by such a cutting device, which will be employed to remove the undesirable material, which will be discharged onto one

45 of the conveyors *k* or *l*, which will be operated in reversed direction to carry the undesirable material to the outer entry *d*, while the other conveyor is carrying the material severed by the mining machine to the middle entry, where it is loaded and transported from the mine. The undesirable material may be deposited in the outer entry and left to be covered by the falling of the mine roof.

What I claim as new and desired to secure

55 by Letters Patent of United States is:—

1. In a mining machine, the combination with a comparatively narrow upright supporting frame in an upright plane extending longitudinally of the mine wall, loop chain core cutting mechanism having an unobstructed core opening therethrough and carried at one of the lateral faces of said frame on a substantially horizontal axis for feeding movement to approximately 180°, means for operating said core cutting mecha-

nism including upright feed thereof on such horizontal axis to cut a crescent-shaped mass of material from the mine wall, and means for discharging at the other lateral face of said frame material of the cut core in comparatively large pieces. 70

2. In a mining machine, the combination with a comparatively narrow upright frame adapted to extend along a mine wall while spaced therefrom, said frame having an unobstructed core opening extending transversely therethrough from the mine wall rearwardly, cutting mechanism carried by said frame and extending therefrom toward the mine wall, and means for discharging 75 the dislodged material through the opening in said frame to the lateral face thereof opposite the cutting mechanism. 80

3. In a mining machine, the combination with cutting mechanism, of means for operating said cutting mechanism, means for transferring the cut material back from the mine wall, and a substantially rectangular upright frame for supporting said cutting mechanism at one side thereof and having 85 an unobstructed opening therethrough for the passage of transferred material, said upright frame being comparatively narrow 90 in the direction of transfer of such material. 95

4. In a mining machine comprising a narrow upright supporting frame adapted to be located in a mine chamber to extend along the face of the mine wall in an upright plane spaced from the wall, dislodging mechanism mounted on said frame for support thereby parallel to the mine wall on that side thereof facing the mine wall, and means for operating said dislodging mechanism to remove material from the mine wall for delivery to a conveyor extending along said 105 frame on that side thereof remote from the mine wall. 100

5. In a mining machine, the combination with a narrow rectangular upright supporting frame having a free and unobstructed space back thereof for the passage 110 of dislodged material parallel to the mine wall and adapted to extend along a mine wall in a plane substantially perpendicular to the floor and roof of the mine chamber 115 spaced back from the face of the mine wall, of dislodging mechanism mounted on said frame for support thereby to extend therefrom to the mine wall in a direction transversely of such frame, and means for operating 120 said dislodging mechanism to remove material from the mine wall for delivery back from the mine wall through such plane to that side of said frame which is remote from the mine wall. 125

6. In a mining machine, the combination with a comparatively narrow upright frame having an unobstructed core opening therethrough, of means for supporting said frame for movement in the direction of the 130

- upright lateral faces thereof, severing mechanism carried by said frame to extend from one of the lateral faces of said narrow upright frame, and means for operating 5 said severing mechanism including feeding movement thereof transversely relatively to an upright plane and extending through said narrow frame to cut a core in position to move rearwardly transversely through the 10 said unobstructed core opening.
7. In a mining machine, the combination with a narrow rectangular upright open supporting frame movable in the direction of the lateral faces thereof, of severing mechanism carried by said frame at one of the lateral faces thereof for operation transversely of said lateral faces in planes extending substantially at right angles to an upright plane extending through said supporting frame, and means for transferring material dislodged by said severing mechanism through said frame and from the opposite lateral face thereof.
8. In a mining machine, the combination with a narrow upright rectangular open supporting frame adapted for movement in the direction of the lateral faces thereof, of means for securing said frame in fixed upright position, severing mechanism carried wholly by said supporting frame to extend from one of the lateral faces thereof and in position to operate transversely of an upright plane extending through said frame from one end to the other thereof, and means 30 for operating said severing mechanism including feeding movement thereof in planes extending transversely of the longitudinal upright plane of said supporting frame.
9. In a mining machine, the combination with an upright narrow frame adapted to be located in a mine chamber between the floor and roof thereof in an upright plane extending along a mine wall and spaced therefrom, the space back of said frame being free and unobstructed for the passage of material parallel to the mine wall, of a plurality of rollers in such plane for supporting said frame for movement in the direction of the lateral faces of said frame while 45 remaining substantially in said plane, dislodging mechanism mounted on said frame for support thereby to extend toward the mine wall transversely of such plane and from the lateral face of said frame adjacent the mine wall, and means for securing said frame in fixed upright position in such plane during the operation of said dislodging mechanism.
10. In a mining machine, the combination with a supporting frame having spaced-apart uprights connected at their top and bottom horizontally to form an open rectangular structure narrow between the front and rear faces thereof in a direction extending transversely of the mine wall, of 60
- core cutting mechanism having an unobstructed core opening therethrough and mounted on the front face of said structure, means for operating said core cutting mechanism to dislodge a core of material from a mine wall in advance of the front face of said structure, and means for moving such core material from the mine wall through the opening in said rectangular structure to a free and unobstructed space back of said structure and adjacent the rear face of said frame.
11. In a mining machine, the combination with a supporting frame comparatively narrow between front and rear faces thereof in a direction extending transversely of the mine wall, of cutting mechanism mounted on said frame to extend toward the mine wall from the front face of said frame, means for operating said cutting mechanism including swinging feeding movement thereof on a horizontal axis substantially parallel to the front and rear faces of said frame, and means for adjusting the elevation of said axis of swing of said cutting mechanism to vary the cutting stroke of said cutting mechanism on that side of said frame facing the mine wall.
12. In a mining machine, the combination with a substantially rectangular frame comparatively narrow in a direction extending transversely back from the mine wall, said frame having a free and unobstructed space back of the same extending parallel thereto and being adapted to be located in a mine chamber in a plane extending along the face of the mine wall and spaced therefrom, of cutting mechanism supported by said frame on that side thereof adjacent the mine wall for feeding movement about a substantially horizontal axis parallel to such upright plane, and means for operating said cutting mechanism including feed thereof on such horizontal axis through an arc extending intermediate the floor and roof of the mine chamber.
13. In a mining machine, the combination with a supporting frame comparatively narrow in a direction extending transversely back from the mine wall, of brackets extending from that side of said frame facing the mine wall, said brackets extending transversely of said frame toward the upright mine wall, and cutting apparatus supported entirely by said brackets for arcuate feeding movement relatively to said frame on a general horizontal axis substantially parallel to an upright plane extending longitudinally through said supporting frame.
14. In a mining machine, the combination with a supporting frame comparatively narrow in a direction extending transversely back from the mine wall, of upright supports at the ends of said frame, brackets mounted on said frame to extend from one

- side thereof toward an upright mine wall, mechanism for adjusting the elevation of said brackets on said supporting frame, core cutting mechanism having an unobstructed 5 core opening therethrough and mounted on said brackets for sole support thereby, said core cutting mechanism being adjustable in elevation together with said brackets, and means for operating said core cutting mechanism 10 including feeding movement thereof along arcuate lines in planes substantially perpendicular to an upright plane extending longitudinally through said supporting frame.
- 15 15. In a mining machine, the combination with an upright supporting frame adapted to be located in an upright plane extending along a mine wall and spaced therefrom, said frame having its narrowest dimension in a 20 direction extending back from the mine wall transversely of such plane to afford a free and unobstructed space back of said frame for the passage of dislodged material parallel to the mine wall, of brackets carried by 25 said frame to extend from that side thereof facing the mine wall, cutting mechanism mounted on said brackets for feeding movement about a substantially horizontal axis parallel with one of the lateral faces of said 30 frame and intermediate the mine wall and said frame, and means for operating said cutting mechanism in upright planes substantially perpendicular to the longitudinal plane of said frame in advance of said free and unobstructed space.
16. A mining machine, comprising an upright frame; brackets carried by said frame for vertical adjustment thereon; a core cutter carried by said brackets for rotation 40 about a horizontal axis; and means for shifting said cutter relative to said axis of rotation.
17. A mining machine, comprising an upright frame; a core cutter carried by said frame for rotation about a horizontal axis; means for adjusting said axis of rotation on said frame; and means for shifting said cutter relative to said axis of rotation.
18. A mining machine, comprising an upright frame; a loop core cutter carried by said frame for rotation about a horizontal axis; means for adjusting the axis of rotation of said cutter relative to said frame; and means for varying the radial length of 55 said cutter relative to said axis of rotation.
19. A mining machine, comprising a supporting frame; a hollow axle carried by said frame for rotation about a horizontal axis; a loop core cutter carried by said axle; means for adjusting said axis of rotation vertically relative to said frame; and means for shifting said axle and cutter relative to said axis of rotation.
20. In a mining machine, a supporting 60 frame-work; brackets carried by said frame- work for vertical adjustment thereon; supporting members journaled in said brackets for rotation about a horizontal axis; a hollow axle carried by said supporting members for rotation therewith about said horizontal axis; a loop core cutter carried by said hollow axle; and means for adjusting said axle and cutter relative to said horizontal axis of rotation to vary the effective radius of said core loop cutter. 70
21. In a mining machine, an upright frame-work; brackets carried by said frame-work for vertical adjustment thereon; supporting members journaled in said brackets for rotation about a horizontal axis; a hollow axle carried by said supporting members; a loop cutter carried by said hollow axle; means mounted in said axle for operating said cutter; and means for adjusting said axle and cutter relative to the axis of rotation of said supporting members to vary the effective radius of said loop cutter. 75
22. In a mining machine, a cutter head comprising an axle; a loop cutter carried by said axle; a support for said axle; and means for connecting said axle to said support for vertical adjustment relative thereto to vary the effective radius of said loop cutter while the latter is supported by the floor of the mine chamber. 90
23. In a mining machine, the combination with a supporting frame, of an axle, supporting discs for opposite ends of said axle journaled in said supporting frame for rotation about a common axis, cutting mechanism mounted on said axle and comprising a cutter frame, and adjusting connections between said axle and said cutting frame for varying the effective radius of said cutting mechanism relative to said axis. 100
24. In a mining machine, a cutter head comprising an axle; spaced-apart supporting discs for opposite ends of said axle journaled for rotation about a common axis; 110 sliding connections between said axle and said discs; and means for adjusting said axle on said sliding connections relative to the axis of rotation of said discs.
25. In a mining machine, a cutter head comprising an axle, cutting mechanism carried by said axle; supporting discs for the ends of said axle journaled for rotation about a common axis; sliding connection between said axle and said discs; and means for moving said axle on said sliding connection to vary the effective radius of said cutting mechanism as it rotates about the axis of rotation of said discs. 115
26. In a mining machine, the combination with a horizontal axle, of cutting mechanism carried by said axle to rotate bodily therewith, a frame having spaced-apart bearings, spaced-apart supports for the ends of said axle, said spaced-apart supports be- 120
- 130

- ing journaled in said bearings for rotation about a horizontal axis, means for vertically adjusting said spaced-apart bearings to effect vertical adjustment of said horizontal axis, sliding connections between said supports and said axle, and rack and pinion mechanism for adjusting said axle and said cutting mechanism relative to said supports and relative to said horizontal axis to vary the effective radius of feeding movement of said cutting mechanism about said horizontal axis.
27. In a mining machine, a cutter head comprising a hollow axle; supports for the ends of said axle journaled for rotation about a horizontal axis; sliding connection between said supports and the ends of said axle; racks carried by said supports; a shaft carried by said axle and pinions secured to said shaft for adjusting said axle or sliding connection relative to said supports.
28. In a mining machine, a cutter head comprising a horizontal axle; supports for the ends of said axle journaled for rotation about a common axis; sliding connection between said supports and the ends of said axle; racks carried by said supports; a shaft carried by said axle and extending longitudinally thereof; pinions carried by said shaft and meshing with said racks; and worm gearing for rotating said shaft to move said axle on said sliding connection relative to said supports.
29. In a mining machine, a cutter head comprising a horizontal hollow axle; supports for the ends of said axle journaled for rotation about a horizontal axis; rack and pinion mechanism for adjusting said axle relative to said supports; worm gearing for operating said rack and pinion mechanism; and means for adjusting the axis of rotation of said supports.
30. A mining machine, comprising a frame; brackets secured to said frame for vertical adjustment thereon; supporting discs journaled in said brackets for rotation about a horizontal axis; slideways carried by said discs; a hollow axle having its ends supported by said slideways; a loop cutter carried by said hollow axle; rack and pinion mechanism carried by said axle for adjusting said axle and said loop cutter on said slideways to vary the effective radius of said cutter; and means for operating said rack and pinion mechanism and for holding said axle in adjusted position.
31. In a mining machine, the combination with an upright flat frame comparatively narrow in a direction extending transversely back from an upright mine wall to afford a free and unobstructed space back of the same for the passage of dislodged material parallel to the mine wall, said frame being adapted to be moved successively into new positions along the face of the mine wall, of cutting mechanism carried by said frame on that side thereof facing the upright mine wall, and means for operating said cutting mechanism transversely of the upright longitudinal plane extending through said frame in advance of said free and unobstructed space, to remove from the mine wall a continuous section of material along the mine wall.
32. In a mining machine, the combination with a portable supporting frame movable along a mine wall approximately parallel thereto and spaced therefrom, said frame being comparatively narrow in a direction back from the face of the mine wall transversely of said frame to afford a free and unobstructed space back of said frame for the passage of dislodged material parallel to the mine wall, of mechanism mounted on said frame for engaging the roof of a mine chamber to hold said frame in anchored position, said anchoring mechanism being located in an upright plane extending through said frame and the path of movement of the latter, cutting mechanism carried by said frame and extending toward the mine wall from that side of said frame facing the mine wall, and means for operating said cutting mechanism including feed thereof in planes extending transversely of said frame.
33. In a mining machine, the combination with a supporting frame having front and rear upright faces a comparatively short distance apart, of means for moving said frame along the face of a mine wall in a direction parallel with said faces, a loop chain core cutter having an unobstructed core opening therethrough and mounted on the front face of said frame for arcuate feeding movement about a horizontal axis parallel with the direction of movement of said frame, and means for operating said core cutter including feeding movement on such horizontal axis to sever a core of material in advance of the front face of said frame and in position to cause the cut core to extend through such unobstructed opening and through an opening in said supporting frame for passage to an unobstructed space back of the rear face of said frame and adjacent to said rear face.
34. In a mining machine, the combination with a narrow upright supporting frame having a free and unobstructed space back of the same for the passage of dislodged material parallel to the mine wall, of means for moving said frame in the direction of the lateral faces thereof parallel to the mine wall, a core cutter having an unobstructed core opening therethrough and supported at that side of said frame facing the mine wall, said core cutter being supported on said frame for arcuate movement

- relatively thereto about an axis parallel to the direction of movement of said supporting frame, and means for operating said core cutter including feed thereof along lines in planes perpendicular to the path of movement of said frame, whereby large blocks of material may be cut from the mine wall to dislodge a continuous section from the face of the mine wall.
35. In a mining machine, the combination with a supporting frame, of cutting mechanism mounted on said frame and having an unobstructed core opening therethrough, means for operating said core cutting mechanism including feed thereof in planes transversely of the plane passing through the path of travel of said frame, means for moving said frame, together with said cutting mechanism, along the face of the mine wall in a direction approximately parallel therewith to position the machine for successive contiguous cuts, and a guard carried by said frame and arranged to enclose the surface exposed by the removal of the next preceding core.
36. In a mining machine, an upright frame; means for removing a section of material at one side of said frame; means for moving said frame in either direction along the face of a mine vein; and a pair of guard plates carried one at each end of said frame adjustable into and out of operative position independently of one another to bring one of said plates into operative position for each direction of movement of said machine.
37. In a mining machine, the combination with a supporting frame comparatively narrow in a direction extending transversely from the mine wall to afford a free and unobstructed space back of said frame for the passage of dislodged material parallel to the mine wall, of cutting mechanism mounted on said supporting frame for operation at that side thereof facing the mine wall, a monopath support for said frame and capable of moving over the mine floor in a single path of travel, and means on said frame for engaging the roof of the mine chamber to hold said frame in a predetermined position against said monopath support during the operation of said cutting mechanism.
38. In a mining machine, the combination with a flat main frame adapted to be located substantially parallel to a mine wall in a position spaced therefrom, of rollers in alinement with each other to afford a monopath support for said main frame in a plane extending along said path and longitudinally through said frame cutting mechanism carried by said frame for operation at that side thereof facing the mine wall, and means for firmly holding said frame in a predetermined position while supported by said monopath support and during the operation of said cutting mechanism.
39. In a mining machine, the combination with a supporting frame, of cutting mechanism mounted thereon and extending from one side thereof, the other side of said frame being free and unobstructed for the passage of dislodged material parallel to the longitudinal upright plane of said frame, spaced-apart rollers mounted in alinement with each other at the lower portion of said frame in such upright plane, and spaced apart roof jacks mounted on said frame approximately in alinement with each other and in such plane to anchor said frame during the operation of said cutting mechanism and while said space adjacent said upright plane remains free and unobstructed.
40. In a monopath mining machine, the combination with an upright supporting frame comparatively narrow between its front and rear upright faces, of roller supports for the lower edge of said narrow upright supporting frame, means for holding said frame in an upright position in a mine chamber, said holding means comprising a pair of pointed bars carried by said frame and having screw threaded means for forcing the pointed ends of said bars into contact with the roof of the mine chamber, and cutting apparatus supported by said frame and extending forward from the upright front face thereof.
41. In a monopath mining machine, the combination with a rectangular supporting frame comparatively narrow between the upright front and rear faces thereof, of rollers, one in each of the lower corners of said frame for supporting the latter in a monopath of travel, roof jacks carried by said frame one at each of the upper corners thereof in position to hold said frame in upright position, and cutting apparatus supported on said frame to extend forward from the upright front face thereof.
42. The combination with a mono-path mining machine comprising a narrow supporting frame having upright front and rear faces and cutting mechanism extending from the front face, of alined wheels for supporting said frame for movement in an upright plane extending between such faces of said frame, a motor carried by said frame, a rope drum carried by said frame and connected for operation to said motor, and a cable connected to said drum and wound thereon and adapted to have its free end anchored in the mine to effect movement of said frame as aforesaid when said drum is operated, to adjust the position of said cutting mechanism.
43. In a mining machine, the combination with a supporting frame having spaced apart uprights, of a cross-bar fixed to said

- uprights to connect the same, an additional cross-bar connecting said uprights and slideable up and down on the same, cutting mechanism carried by said additional cross-bar 5 for swinging movement on a horizontal axis, and means connecting said fixed and movable cross-bars for adjusting said movable bar and said cutting mechanism in elevation relatively to said frame to vary the position 10 of said axis.
44. In a mining machine, a frame; spaced uprights on said frame having an unobstructed core-opening between the same; a fixed bar connecting the upper ends of said uprights; a movable bar having its opposite ends slidably mounted on said uprights; a core cutter carried by said movable bar; and a threaded rod connecting said fixed and movable bars for adjusting said movable 15 bar on said uprights.
45. In a mining machine, the combination with a frame comparatively narrow in a direction extending transversely of the mine wall, of spaced-apart uprights carried by 20 said frame, a shelf fixed to said uprights, a motor mounted on said shelf, severing mechanism supported by said frame, means for driving said severing mechanism, means operated by said motor for feeding said severing mechanism along lines in planes perpendicular to the upright longitudinal plane of said frame, and means for transferring the dislodged material to a space back of 25 said frame adjacent its upright longitudinal plane for passage along a mine wall back of 30 said plane and adjacent thereto.
46. In a mining machine, the combination with a supporting frame having spaced apart uprights, of a shelf connecting said 35 uprights, cutting mechanism mounted on said frame for operation on an upright wall adjacent said frame, said cutting mechanism comprising a rotary cutter-head supported on said uprights for arcuate feeding movement on a horizontal axis, a sheave secured 40 to said cutter-head, a rope drum carried by said uprights, a cable connecting said drum and said sheave, and a motor mounted on said shelf to drive said drum and wind 45 said cable thereon to rotate said cutter-head on such horizontal axis and thereby effect 50 swinging feeding movement of said cutting mechanism during the actuation thereof.
47. In combination, a narrow upright rectangular mining machine frame; a loop cutter carried at one side of said frame; an elongated drum mounted on the lower portion of said frame; and a sling having one end secured to said loop cutter and the other 55 end secured to said drum and arranged to receive the material severed by said cutter.
48. In combination, a narrow upright rectangular mining machine frame; a loop cutter mounted for rotation about a horizontal 60 axis at one side of said frame; an elongated 65
- drum mounted near the base of said frame and having its axis parallel with the axis of said loop cutter; and a sling having one end secured to said loop cutter and the other end secured to said drum and arranged to be drawn by said cutter into the kerf formed thereby during the severing operation of 70 said cutter and to be wound on said drum to transfer the material from its severed position after the severing operation.
49. In combination, a narrow upright rectangular frame; a cutter head mounted for rotation about a horizontal axis at one side of said frame and having a loop cutter secured thereto; a drum mounted for rotation near the base of said frame and having its axis of rotation parallel with the axis of rotation of said cutter head; and a sling having its opposite ends secured to said loop 75 cutter and drum respectively and arranged to be wound on said drum to transfer the material severed by said cutter from its native position in the mine wall through said frame to a position on the side thereof opposite 80 said cutter head.
50. In a mining machine, the combination with an upright supporting frame comparatively narrow in a direction extending transversely of the mine wall to afford a free and unobstructed space at the rear of 85 said frame adjacent the longitudinal upright plane thereof for the passage of material along such space approximately parallel to the mine wall, of cutting apparatus carried at that side of said frame facing the mine wall, means for operating said cutting mechanism, including feeding movement thereof along lines in planes extending transversely of the longitudinal plane of said frame, and guard mechanism 90 supported by said frame for preventing the disconnected material from falling onto 95 parts of said operating means.
51. In a system of mining, the combination of a mining machine having a supporting frame with its narrowest dimension extending transversely back from the mine wall, said frame being adapted to be located in the mine chamber to extend along 100 the mine wall in a plane spaced back from the mine wall and parallel thereto, cutting mechanism mounted on that side of the said frame which faces the mine wall, and conveyer mechanism located at the opposite side of said frame substantially parallel 105 to said plane and parallel to said mine wall, said mining machine comprising means for transferring the severed material onto said conveying mechanism.
52. In a system of mining, the combination with a narrow upright supporting frame adapted to be located in a mine chamber with its lateral faces extending along a mine wall and spaced back a short 110 distance therefrom to afford a free and un- 115

- obstructed space back of the frame, of cutting mechanism mounted on that side of said frame facing the mine wall, means for operating said cutting mechanism transversely of said narrow frame, conveyer mechanism mounted adjacent that side of said frame remote from the mine wall to extend along the mine wall substantially parallel to said narrow frame and to said mine wall, and means for transferring the material severed by said cutting mechanism from its native position in the mine wall onto said conveyer mechanism for removal along the mine wall in a direction substantially parallel to said narrow frame and through said unobstructed space.
53. In a system of mining, the combination with a mining machine comprising a frame narrow between front and rear faces thereof and cutting mechanism extending toward the mine wall from the front face thereof, of means for moving said mining machine along a path substantially parallel to said faces, a mechanical conveyer to carry material, means for supporting said conveyer approximately parallel with the face of the mine wall and substantially parallel with the rear face of said mining machine, and mechanism for transferring the material severed by said cutting mechanism from its native position onto said conveyer in the various adjusted positions of said mining machine along the mine wall in front of said conveyer.
54. In a mining and loading system, the combination with a conveyer, of means for supporting said conveyer to move dislodged material approximately parallel with the upright face of a mine wall, said supporting means comprising a plurality of mine supports each having an arm extending toward the face of the mine wall, a mining machine comprising an upright frame comparatively narrow in a direction transverse of said conveyer and having cutting mechanism mounted on that side of said frame facing the mine wall, and means for transferring severed material transversely through an opening in said narrow frame onto said conveyer.
55. In a mining machine, the combination with a supporting frame comparatively narrow between the front and rear faces thereof to afford an upright free and unobstructed passageway for movement of dislodged material back of said frame and substantially parallel to the longitudinal upright central plane thereof, of core cutting mechanism having an unobstructed core opening therethrough and mounted on the front face of said supporting frame in position to move relatively to said frame on a substantially horizontal axis to cut an upright crescent-shaped core of material in a mine wall, means for operating said core cutting mechanism including upright feeding movement on such horizontal axis to cut such a core, and means for transferring the core material directly from its cut position at the mine wall into position back of the rear face of said frame for movement along said unobstructed passageway.
56. In a mining machine, the combination with a frame, of means carried by said frame for cutting a core of material from a mine wall, a sling connected at one end to said core-cutting means and comprising a plurality of ropes, means for exerting a pull on the other end of said sling, said sling being arranged to receive material cut by said core-cutting means, and means for regulating the winding of said ropes.
57. In a mining machine, the combination with a supporting frame, of core cutting apparatus mounted thereon, a sling comprising a plurality of spaced-apart ropes connected to said core cutting apparatus to receive the cut material therefrom, tensioning mechanism comprising a rope drum on which said ropes are adapted to be wound, and means for regulating the winding of said ropes on said drum to effect the winding thereof in uniform concentric layers in alignment with each other along the exterior surface of the drum.
58. In a mining and loading machine, the combination with a supporting frame, of core cutting mechanism having an unobstructed core opening therethrough and mounted on said frame, a sling arranged to receive core material from said core cutting mechanism, a drum mounted on said frame for the winding of the sling thereon, means for rotating said drum to wind the sling thereon, and mechanism for moving the drum along its axis while being rotated to effect the winding of said sling in a layer on said drum.
59. In a mining machine, the combination with a frame, of a cutter mounted on said frame to swing on a horizontal axis during its feed, an elongated drum mounted on said frame, a sling having one end secured to said cutter to receive material therefrom, and the other end secured to said drum, and means effecting the winding of said sling on said drum to transfer the material from its severed position after the severing operation.
60. In a mining machine, the combination with a narrow upright frame, of core-cutting mechanism mounted on said frame, a flexible sling connected to said core-cutting mechanism for receiving material therefrom, a drum having a horizontal axis at the lower portion of an opening through said upright frame, and means for effecting

rotation of said drum to wind said flexible sling thereon while the dislodged material is transferred through said opening.

61. In a mining and loading machine, the combination with a supporting frame, narrow between its upright front and rear faces in a direction extending transversely of the mine wall, of mechanism mounted thereon for dislodging from a mine wall in comparatively large blocks, an upright crescent-shaped section of material, and loading apparatus acting on the dislodged material to transfer the same directly from its cut position toward loading position.

62. In a mining machine, the combination with a supporting frame, of brackets carried by said frame and extending laterally therefrom in spaced-apart positions, core cutting mechanism having an unobstructed core opening adjacent an axle with its end portions supported respectively by said brackets, means for adjusting the elevation of said brackets relatively to said supporting frame to adjust the elevation of said axle and said core cutting mechanism, and means for operating said core cutting mechanism including arcuate feeding movement thereof on an axis extending through said axle.

63. In a mining machine, the combination with a supporting frame, of kerf cutting mechanism having a swinging feeding movement on a substantially horizontal axis, spaced-apart supports mounted on said frame each directly supporting said cutting mechanism on said frame, means for vertically adjusting said spaced-apart supports on said frame to adjust the elevation of said horizontal axis, and means for shifting the kerf cutting mechanism relatively to said axis of feeding movement to vary the radial length of the kerf cutting mechanism relatively to said axis.

64. In a mining machine, the combination with a supporting frame, of core cutting mechanism having an obstructed core opening therethrough and carried by said frame for arcuate feeding movement on a predetermined axis, means for adjusting the position of said core cutting mechanism bodily and rectilinearly relatively to said frame to vary such axis of feeding movement, means for varying the radial length of said cutter relatively to such axis, and means for operating said core cutting mechanism including the feeding movement thereof on such axis in its adjusted position.

65. In a mining machine, the combination with a supporting frame, of an axle carried by said frame for rotation about a predetermined axis, core cutting mechanism having an unobstructed core opening therethrough and carried by said axle, means for vertically adjusting the position of said cutting mechanism relatively to said frame to

vary the position thereof relative to said axis on said frame, and means for operating said core cutting mechanism including arcuate feed thereof on said axis in the adjusted position of said cutting mechanism.

66. In a mining machine, the combination with a supporting frame, of brackets carried by said frame for adjustment thereon, supporting members journaled in said brackets for rotation about a predetermined axis, an axle carried by said supporting members for rotation therewith about such axis, core cutting mechanism having an unobstructed core opening therethrough and carried by said axle, means for adjusting said core cutting mechanism relatively to said supporting members to vary the effective radius of said core cutting mechanism.

67. In a mining machine, the combination with a supporting frame, of core cutting mechanism having an unobstructed core opening therethrough and mounted on said frame, means for operating said core cutting mechanism including upright arcuate feeding movement thereof to cut an upright crescent-shaped core in a mine wall, and a pair of guard plates carried one in each end of said frame adjustable into and out of operative position independently of one another to bring one of said plates into operative position for each direction of movement of the machine to a new location along the mine wall.

68. In a mining machine, the combination with a supporting frame, of a guard plate pivotally connected thereto for relative adjustment, loop chain core cutting mechanism having an unobstructed core opening therethrough and mounted on said frame adjacent said guard plate, and means for operating said core cutting mechanism including arcuate feeding movement thereof relatively to said supporting frame and adjacent said guard plate.

69. In a mining machine, the combination with a supporting frame, of a guard plate pivotally connected thereto, means for securing said guard plate to said frame in adjusted position, loop chain core cutting mechanism mounted on said frame near said guard plate for arcuate feeding movement relatively to said frame, and means for operating said core cutting mechanism including arcuate feeding movement thereof relatively to said guard plate.

70. In a mining machine, the combination with a supporting frame, of an upright guard plate pivotally connected at its rear portion to said frame and having a forward arcuate edge, core cutting mechanism mounted on said frame adjacent said guard plate for swinging movement on a substantially horizontal axis, and means for operating said core cutting mechanism including upright arcuate feeding movement there-

of relatively to said guard plate while the latter occupies a position at the side of the core to prevent material from the core from being scattered from the range of feeding movement of said core cutting mechanism beyond the plane of said guard plate.

71. In a mining machine, the combination with a supporting frame, of spaced-apart upright guard plates each pivotally connected to said frame and each having a forward arcuate edge, separate means for securing each of said guard plates to said frame in adjusted position either extending forwardly in a predetermined position or upwardly in a predetermined position, core cutting mechanism mounted on said frame for upward swinging movement on a horizontal axis to cut an upright crescent-shaped core in a mine wall between the upright planes of said guard plates, and means for operating said core cutting mechanism including upward arcuate feeding movement thereof on such horizontal axis to cut such crescent-shaped core while said guard plates remain in substantially stationary positions.

72. In a mining machine, the combination with a supporting frame having spaced-apart uprights, of loop chain core cutting mechanism having an unobstructed core opening therethrough, a supplemental frame for connecting said core cutting mechanism to said uprights for rectilinear adjustment in elevation, and means for adjusting the elevation of said supplemental frame rectilinearly to vary the elevation of said core cutting mechanism relatively to said first named frame.

73. In a mining and loading machine, the combination with a supporting frame, of core cutting mechanism having an unobstructed core opening therethrough and mounted on said frame for arcuate feeding movement, a rope drum mounted on said frame, a sling having one end secured to said core cutting mechanism and the other end connected to said rope drum, means for operating said rope drum to cause said sling to move material of the core toward loading position, and means for effecting axial movement of said drum during its rotation.

74. In a mining machine, the combination with a supporting frame, of a core cutting having an unobstructed core opening and mounted on said frame, a rope drum mounted on said frame, a sling connected at one end to said core cutter and at the other to said rope drum, means for operating said rope drum to wind said sling thereon and effect transfer of material of the core by said sling away from the mine wall, and means for automatically shifting said drum axially.

75. In a mining machine, the combination

with a comparatively narrow supporting frame adapted to be located in a mine chamber for movement along a mine wall in an upright plane substantially parallel thereto and spaced back therefrom, of cutting mechanism mounted on said frame on that side thereof facing the mine wall and for operation in planes extending transversely of the plane through said narrow frame and the path of movement thereof, roof jack mechanism carried by said frame for anchoring the latter in upright position, a cross-piece at the lower portion of said frame, the upper surface of which forms an inclined plane extending upwardly through an opening in said frame toward the rear side thereof and the lower edge of said cross-piece being adapted to contact with the mine floor when said roof jack mechanism is released, thereby limiting the tilting of said frame toward the mine wall, and mechanism for transferring dislodged material from the mine wall over said inclined plane through the opening in said frame.

76. In a mining machine, the combination with a narrow supporting frame adapted to be located in a mine chamber for movement along an upright plane spaced back from the mine wall and substantially parallel thereto, the narrow dimension of said frame being transversely of such plane, of cutting mechanism mounted on said frame on that side thereof facing the mine wall and for operation in planes transversely of the plane through the path of movement of said frame, roof jack mechanism for anchoring said frame during the operation of said cutting mechanism, a plurality of wheels mounted on the lower portion of said frame in alinement with each other and in the plane of movement of said frame, and a plurality of spaced-apart devices extending from the lower portion of said frame on that side thereof facing the mine wall to occupy a position having a clearance from the floor of the mine chamber when said frame is anchored and contacting with the floor of the mine chamber when said anchoring mechanism is released to limit the tilting movement of said frame toward the mine wall.

77. In a mining machine, the combination with a supporting frame having spaced-apart brackets with bearings at their outer ends, of spaced-apart supplemental frames journalled respectively in said bracket bearings on a predetermined substantially horizontal axis, a hollow axle mounted between said spaced-apart supplemental frames for movement relatively thereto and radially with respect to said axis, and also for arcuate movement with said supplemental frames on said axis, loop chain core cutting mechanism carried by said axle for bodily movement there-

- with both radially and arcuately, and mechanism connected between said axle and said supplemental frames for adjusting the position of said axle and said loop chain core cutting mechanism radially relatively to said axis to vary the effective radius of feeding movement of said loop chain core cutting mechanism.
78. In a mining machine, the combination 10 with a supporting frame having spaced-apart bearings, of supplemental spaced-apart frames journalled in said spaced-apart bearings for rotation on a predetermined axis, an axle frame mounted between said supplemental frames, loop chain core cutting mechanism comprising a cutter frame having an unobstructed core opening therethrough and connected to said axle frame to move bodily therewith, and means for adjusting said axle frame and said core cutting mechanism to vary the effective radius of the latter relative to said predetermined axis.
79. In a mining machine, the combination 15 with an axle, of core cutting mechanism having an unobstructed core opening therethrough and comprising a cutter frame connected to said axle and extending radially therefrom, spaced-apart supports for the opposite ends of said axle journalled for rotation about a predetermined axis, and self-locking mechanism for adjusting the effective radius of said core cutting mechanism relative to said predetermined axis.
80. In a mining machine, the combination 20 25 with a supporting frame having spaced-apart bearings, of spaced-apart supplemental frames journalled in said bearings for rotation on a predetermined axis, an axle carried by said supplemental frames and located between the same, loop chain core cutting mechanism having an unobstructed core opening therethrough and mounted on said axle to extend radially therefrom, means mounted on said axle for actuating said loop chain core cutting mechanism, means for moving said supplemental frames, said axle and said loop chain core cutting mechanism arcuately to effect arcuate feed of said core cutting mechanism during actuation thereof, 30 sliding connections between the ends of said axle and said supplemental frames, rack and pinion connections between said supplemental frames and said axle, and means comprising locking worm gearing for operating said rack and pinion connections to move said axle and said loop chain core cutting mechanism along said sliding connections relative to said supplemental frames to adjust the effective radius of said core cutting mechanism relatively to the axis of rotation of said supplemental frames in said spaced-apart bearings.
81. In a system of mining, the combination 35 with a supporting frame, of core-cutting mechanism mounted on said frame and comprising a loop having an unobstructed core opening therethrough, means for operating said core-cutting mechanism to cut a core of material extending through such unobstructed core opening, a conveyer adjacent the path of travel of said frame, and means mounted on said frame for transferring the cut material directly onto said conveyer.
82. In a mining and loading machine, the combination with a conveyer comprising an 40 elongated frame adapted to rest on the floor of a mine chamber parallel to a mine wall and spaced therefrom, said conveyer comprising a traveling element having superimposed portions traveling in opposite directions, of means for operating said conveyer, means for dislodging adjacent upright sections of material from the mine wall and automatically directing it onto said conveyer while the frame of the latter remains in stationary position, and mechanism at that side of said conveyer frame adjacent the mine wall for guiding said dislodging means along said stationary frame over the mine floor of a mine chamber in the space between said frame and the unmined mass.
83. In a mining and loading machine, the combination with an endless conveyer having superimposed portions traveling in opposite directions, of an elongated stationary 45 conveyer frame, means for operating said conveyer, mechanism for cutting upright sections of material from the mine wall and directing it onto said conveyer at various positions along said conveyer frame, and means for guiding said cutting mechanism along said conveyer while moving over the mine floor between said conveyer frame and the unmined mass.
84. In a mining and loading machine, the combination with a main frame, of an endless traveling conveyer mounted on said main frame, a core-cutting mining machine comprising a single endless loop kerf-cutting device with an unobstructed core-opening extending therethrough, means for guiding said core-cutting mining machine along said main frame intermediate the ends thereof and along an unobstructed space between said main frame and an upright mine wall, means for directing dislodged material from said unobstructed core-opening of said core-cutting mining machine onto said conveyer, and means for operating said conveyer to convey dislodged material toward a loading position while such mining machine occupies various positions intermediate the ends of said conveyer.
85. In a mining and loading machine, the combination with a main frame, of a conveyer mounted thereon, a supplemental frame mounted for longitudinal movement along said main frame, a single endless loop

core-cutting device mounted on said supplemental frame and projecting laterally from one side of said main frame, means for adjusting the elevation of said core-cutting mechanism relatively to said supplemental frame, and means for directing cut material from said cutting mechanism onto said conveyor at the various elevations to which said cutting mechanism is adjusted.

In testimony whereof I have signed my name to this specification, in the presence of two subscribing witnesses, on this 10th day of January, A. D. 1916.

EDMUND C. MORGAN.
